CLAIM

The ornamental design for a bottle cap removing tool, as shown and described.

DESCRIPTION

FIG. 1 is a top plan view of a bottle cap removing tool showing my new design the bottom being a mirror image;

FIG. 2 is a left side elevational view thereof;

FIG. 3 is a right side elevational view thereof;
FIG. 4 is a front elevational view thereof, the rear view being a mirror image;

FIG. 5 is a cross-sectional view taken on line 5—5 of FIG. 1;

FIG. 6 is an enlarged fragmentary view thereof;

FIG. 7 is a top plan view thereof in an alternate position;

FIG. 8 is a rear elevational view of FIG. 7;

FIG. 9 is a left side elevational view of FIG. 7, the right side being a mirror image;

FIG. 10 is a front elevational view of FIG. 7;

FIG. 11 is a top plan view thereof in an alternate position;

FIG. 12 is a rear elevational view of FIG. 11;

FIG. 13 is a left side elevational view of FIG. 11, the right side being a mirror image; and

FIG. 14 is a front elevational view of FIG. 11.

The broken lines in FIGS. 1, 7 and 11 are for illustrative purposes only.
